UNITED STATES PATENT OFFICE.

WALTER GREIG, OF NIAGARA FALLS, NEW YORK, ASSIGNOR TO AMERICAN SALES BOOK COMPANY, LIMITED, OF TORONTO, CANADA, A CORPORATION OF CANADA.

SALES-BOOK.

1,107,295.

Specification of Letters Patent. Patented Aug. 18, 1914.

Application filed January 9, 1912. Serial No. 670,134.

To all whom it may concern:

Be it known that I, WALTER GREIG, a citizen of the United States, residing at Niagara Falls, in the county of Niagara and 5 State of New York, have invented certain new and useful Improvements in Sales-Books, of which the following is a full, clear, and exact description, such as will enable others skilled in the art to which it appertains to make and use the same.

This invention relates to manifolding books.

One of the objects of the present invention is to provide a simple and practical book 15 of the above type which may be conveniently manipulated without soiling the fingers.

Another object is to provide a durable salesbook, having few parts, which will be cheap to manufacture.

20 A further object is to avoid the use of carbonized sheets as much as is consistent with the other objects in view.

Further objects will be in part obvious and in part pointed out hereinafter.

25 The invention accordingly consists in the features of construction, combinations of elements and arrangement of parts which will be exemplified in the construction hereinafter set forth, and the scope of the application of which will be indicated in the following claims.

In the accompanying drawing, wherein is shown one of various possible embodiments of this invention, Figure 1 is a perspective 35 diagrammatic view, showing the complete device ready for operation. Fig. 2 is a central longitudinal sectional view of the book in closed position.

Similar reference characters refer to similar parts throughout the different views of the drawing.

Referring now to the drawing in detail, 1 denotes a rear cover for a pad 2, prolonged in one direction to form a top cover 3 and 45 in the opposite direction to form a binding edge 4. The pad comprises a plurality of sheets bound together along one edge with the cover by means of staples 5 and each sheet is separated by two weakening lines 6 or perforations into a plurality of sections 50 or leaves, in the present case, three, denoted by the numbers 7, 8 and 9, and by a third weakening line 10 near the bound edge, whereby the leaves may be separated from

the stub. One of these leaves 9 of each sheet 55 is carbonized throughout its entire rear surface, as indicated at 11, the other leaves being perfectly plain with the exception of printed matter and lines, not herein shown, according to the use to which the book is put. 60

Bound with the sheets by means of the staples 5 and covering the leaf 7, is a separate carbon sheet 12, as shown more clearly in Fig. 2. By using a separate carbon sheet instead of carbonizing the back of another 65 leaf there is no danger of repeating a record of the transaction indefinitely down through the leaves of the pad. Such a construction would necessitate the use of a stop plate, which element is done away with in the 70 present device.

A convenient method of using a book of this character is substantially as follows:— The top sheet of the pad 2 is swung upwardly over the carbon sheet 12 and then folded down upon itself so that it assumes a zigzag position, as shown in Fig. 1, embracing the carbon sheet 12 between the two plain leaves 7 and 8; the back 11 of the upper leaf 9 acting as a manifolding media for transmitting the impressions to the plain leaf 8 immediately therebeneath. In other words, any transaction recorded upon the folded over leaf 9 would be reproduced upon the plain leaf 8 immediately therebeneath owing to the manifolding material 11, and in turn again reproduced upon the plain leaf 7 beneath the carbon sheet 12. After recording the transaction the entire sheet is detached from the stub along line 19 and separated into separate leaves along the lines 6.

It will be noted from the above description that it is unnecessary to handle the carbon sheet 12 at any time, or to touch the carbonized surface 11 of the sheet 9, thus contributing to the cleanliness of the book and greatly increasing the durability or life of the carbon sheet which otherwise through constant handling would become torn and wrinkled.

Another feature of this construction is the obtaining of two plain records of the transaction recorded, leaving the carbonized record on the sheet 9 to be sent to the office 100 or cashier to be kept on file. This is especially desirable in the case of salesbooks used in connection with handling dress-

goods, for example, where a leaf is usually placed within the package, which if carbonized might soil the goods.

It is thus seen that this invention accomplishes, among others, all of the objects and advantages above set forth.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

Having described my invention, what I claim as new and desire to secure by Letters Patent is:

1. In a manifolding salesbook, in combination, a plurality of normally extended flat sheets bound together along one edge, each sheet being divided by weakening lines into three leaves, one of said leaves being carbonized and adapted to be folded over to coact with another leaf, separate manifolding means between said second leaf and the third leaf when folded into operative position, whereby the transaction may be recorded in triplicate, and a cover bound with 30 said leaves adapted to inclose the sheets.

2. In a manifolding salesbook, in combination, a plurality of normally extended flat sheets bound together at one end forming a stub, each sheet being divided into 35 three leaves, the end leaf being carbonized on its under surface, the remaining leaves being plain, said leaves being adapted to be folded into zigzag form as used, and a separate carbon sheet bound with the sheets at 40 the stub adapted to lie between the two lower leaves when folded into operative position whereby a record is recorded in triplicate on the three leaves.

3. In a manifolding salesbook, in combination, a plurality of normally extended flat sheets bound together at one end forming a stub, each sheet being divided into three leaves, the end leaf being carbonized on its under surface, the remaining leaves being 45 plain, a separate carbon sheet bound with the sheets at the stub adapted to lie between

the two lower leaves when folded into operative position whereby a record is recorded in triplicate on the leaf nearest the stub, and means bound at one end by staples with said 55 sheets adapted to form a top and bottom cover for said device.

4. In a manifolding book, in combination, a plurality of normally extended flat sheets bound together at one end, each sheet being 60 divided into a plurality of parts or leaves separated by weakening lines, the larger number of parts of said sheets being uncarbonized on either side, and a carbon sheet bound with the sheets forming the book 65 adapted to coact with one of the leaves when the leaves constituting the sheet are folded in superimposed relation.

5. In a manifolding book, in combination, a plurality of normally extended flat sheets 70 bound together at one end, each sheet being divided into leaves, the leaf at the free end of each sheet being carbonized on one side and adapted when the leaves are folded in superimposed relation to coact with another 75 leaf, and a carbon sheet bound with said first mentioned sheets extending over one of the leaves whereby a plurality of carbon copies are made on the sheet in use on the recording of each transaction.

6. In a manifolding book, in combination, a plurality of normally extended flat sheets bound together at one end, each sheet being divided into leaves, the leaf at the free end of each sheet being carbonized on one side 85 and adapted when the leaves are folded in superimposed relation to coact with another leaf, and a carbon sheet bound with said first mentioned sheets extending over one of the leaves whereby a plurality of carbon 90 copies are made on the sheet in use on the recording of each transaction, the leaf beneath said carbon sheet being plain on both sides whereby duplicating through to a lower leaf is prevented.

In testimony whereof I affix my signature, in the presence of two witnesses.

WALTER GREIG.
